CLAIM

The ornamental design for a paver edging as shown and described.

DESCRIPTION

FIG. 1 is a front isometric view of a first embodiment of a paver edging;

FIG. 2 is a rear isometric view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a front isometric view of a second embodiment of a paver edging;

FIG. 9 is a rear isometric view thereof;

FIG. 10 is a right side view thereof;

FIG. 11 is a front view thereof;

FIG. 12 is a back view thereof;

FIG. 13 is a top view thereof; and,

FIG. 14 is a bottom view thereof.

The drawings contain a symbolic break. The portion between the break lines forms no part of the claimed design.

1 Claim, 6 Drawing Sheets
